UNITED STATES PATENT OFFICE

146,421

DESIGN FOR A FONT OF TYPE

Melville B. Rapp, Miami Beach, Fla.

Application March 22, 1946, Serial No. 127,795

Term of patent 14 years

(Cl. D64—12)

To all whom it may concern:

Be it known that I, Melville B. Rapp, a citizen of the United States of America, residing in Miami Beach, county of Dade, and State of Florida, have invented a new, original, and ornamental Design for a Font of Type, of which the following is a specification, reference being had to the accompanying drawing, forming part thereof, wherein the drawing illustrates face views of the font of type, showing my new design.

I claim:

The ornamental design for a font of type, substantially as shown.

MELVILLE B. RAPP.
